PROCESS AND APPARATUS FOR MAKING GUT STRINGS

Carl G. Bjorkman, Chicago, Ill.

Application March 20, 1941, Serial No. 384,369

25 Claims. (Cl. 57—35)

In making gut strings for music strings, tennis rackets, surgical use, or other purposes, it is very desirable to have the string of uniform cross section along its entire length, and to have it round in shape, compact in cross section and smooth surfaced. A gut string is usually made by twisting a skein made up of a few fine ribbons cut from membrane. In my prior Patent No. 2,104,730, I disclosed a method of twisting such strings by suspending them in water during the twisting operation, which greatly improved the quality of the finished strings. The present invention is mainly designed as an improvement of the apparatus and method of this prior patent, although it may no doubt be used without the features of the prior patent if such use should, for any reason, be desired. The present invention includes the subject matter of my copending application Serial No. 302,063, filed October 30, 1939, together with improvements thereon, and this application is therefore a continuation in part of said copending application.

In its more basic aspects, the present invention comprises the step of and means for molding the string as it is being twisted. Since the twisting takes place in contact with the molding means, the molding means will tend to make the string more round, smooth and compact. It is especially effective to this end where the various separate fine ribbons are kept in approximately proper relationship prior to the molding by supporting and stretching the skein in a liquid bath. Since the molding means is moved along the entire length of the string, it will also tend to insure uniformity of cross section of the string.

The invention also contemplates, in its preferred form, a series of partitions between the twisting skeins to prevent interference between them. This permits putting the skeins closer together so as to mount more in a tank of convenient width.

Additional advantages and objects of the invention will become apparent from the following description and from the drawings, in which:

Fig. 1 is a plan view of one form of the apparatus chosen for illustration of this invention.

Fig. 2 is a vertical longitudinal section on an enlarged scale of the structure shown in Fig. 1.

Fig. 3 is a transverse vertical section taken approximately on the line 3—3 of Fig. 2.

Fig. 4 is a corresponding view taken on the line 4—4 of Fig. 2.

Fig. 5 is a fragmentary perspective view of the mold shown in Figs. 1, 2 and 3.

Fig. 6 is a vertical transverse cross section

showing a simplified form of the invention in which the molding means is moved along the length of the string by hand.

Fig. 7 is a fragmentary longitudinal cross section taken approximately on the line 7—7 of Fig. 6, showing one cross sectional shape of the simplified molding means.

Figs. 8 and 9 are fragmentary sectional and plan views, respectively, of another modification of the invention.

Fig. 10 is a fragmentary view corresponding to part of Fig. 8 but showing the partitions resting on the mold plates before the latter start to move.

Although the invention is described in detail hereafter, as required by R. S. 4888, the claims are not to be unnecessarily limited by the detailed disclosure, since the invention may take many forms.

Although three forms of the invention have been illustrated, they have all been illustrated in conjunction with a string twisting apparatus such as was described in my prior Patent No. 2,104,730. In this apparatus, a tank 10 is provided which holds a bath of water which suspends the strings while they are being twisted. At one end of the tank are provided a plurality of rotary spindles 11, while toward the other end of this tank, non-rotary spindles 12 are provided. Each of the spindles bears a hook 13 to which loops 14 may be hooked. Each loop 14 is formed by a cord with which a plurality of very fine ribbons of gut are secured together to form the skein or hank 15 to be twisted. Although the spindles could be located below the surface 16 of the water, the spindles 12, at least, are preferably located just above the surface so that with only a slight amount of droop, the skeins will be suspended in or floated on the water. The non-rotating spindles 12 may conveniently be provided with downward extensions to hold their ends of the skeins at or below the surface. In order to apply tension to the skeins during the twisting operation, the non-rotary spindles 12

are mounted for translation or sliding to and from the rotary spindle. In the illustrated form, each is independently slidable in a bracket 17 which may be adjustably positioned along the length of the tank 10 and which is provided with keyhole slots 18 for receiving the intermediate portions of the spindles 12 between fixed collars 20. A cord 22 is secured to each of the spindles 12, extends over a pulley 24 and is drawn taut by a weight 25. The bar 17 is initially positioned so that it is close to the collar 20 closest to the

string 15, so that as the string is shortened by twisting thereof, the spindle 12 may slide in the bar 17 as far as may be necessary to maintain an even tension on the string 15.

The rotary spindles 11 are held against lengthwise movement by collars 29. Each of the spindles 11 is equipped with a worm gear 30 meshing with a worm shaft 31 driven by a motor 32 through suitable gearing 33. A counting switch, indicated diagrammatically at 34, which may initially be closed by the switch lever 35, serves to stop the motor after a selected number of rotations of the worm gear 30 so as to give the strings 15 the exact number of twists desired. The number will, of course, vary with the length of the string and could be varied on account of other conditions such as the size of the string and size or number of the ribbons. Roughly speaking, 75 turns per inch of the string is good practice. The strings, or skeins, are made up in lengths from 2 to 20 feet, or more, according to the use to which they are to be put.

Water is supplied through the inlet pipe 36 and the level of the water is controlled by outlet pipe 37. Since the water and the gut are of approximately the same density, the gut will either float or substantially float in the water so that, except for centrifugal force as it is twisted, it will act as if it were weightless. If one ribbon of the gut happens to be heavier than the others, or slightly longer, it will not sag below the others prior to twisting. This is very desirable because if one ribbon sags below the other prior to twisting, it is likely to be wound on the outside of the others instead of being twisted in among them.

According to the present invention, the apparatus thus far described is improved by the addition of longitudinally movable molding means. In the form shown in Figs. 1-5, this molding means comprises a carriage 41 which is carried by and may be driven longitudinally by screws 42. The carriage may comprise transverse base plates 43 and 44 to which may be secured brackets 46. Each bracket is secured to and rests on a threaded block 47 which rests on one of the screws 42. The base plates 43 and 44 lie below the skeins 15 and may lie at or slightly below the surface of the water. Above the base plate 43 is positioned a holder plate 48 which coacts with the plate 43 to yieldably hold the various skeins 15 so as to tend to confine the twisting of the skeins to that portion of the skeins between the holder plate 48 and the rotating spindle 11. The screws 42 are driven by the gears 33 and 33' at such speed that the movement of the carriage 41 will approximately keep pace with the progression of the twist in the skein 15. For convenience, the plates 43 and 48 together may be termed a sliding clamp.

The base plate 44 may be regarded as a molding base, and it operates in conjunction with a plate 49 which may be termed an upper mold plate. These molding plates 44 and 49 engage the skein within the zone of the twisting action. It may make very little difference whether any of the twisting action takes place to the left of the plate 44 as seen in Fig. 2, or whether it mainly takes place above the plate 44. It is evident, however, that the gripping action of molding plates 44 and 49 will sufficiently oppose the twisting of the skeins 15 so that not all of the twisting action will occur to the left of the mold plate 44 and, hence, at least some of it will occur above the mold plate 44. Expressed differently, the speed of the movement of car-

riage 41 with respect to the speed of the rotation of spindle 11 should be such that a major portion of the twisting action takes place above the mold 44 and so that the twisting is nearly complete in that portion of the skein or string which is to the right of the molding plate 44. Furthermore, the twisting in the portion of the skein to the left of plate 44 should not be tight enough to prevent readjustment of the various ribbons of one skein with respect to one another. If the skein is to be twisted 75 turns per inch, the carriage may be moved approximately an inch for each 75 turns. It is thus apparent that during the twisting of the skein, that portion in which the twisting action is taking place is at the time of the twisting action rotating in contact with the molding plates 44 and 49 so that the projection of any ribbon beyond the others is substantially prevented. In short, the molding plates 44 and 49 mold the skein, as it is twisted, to a round cross section.

It has been the practice heretofore to sand or otherwise abrade the finished string to a round cross section and to polish it. Although the polishing will still be desired and a slight amount of sanding may often also be desirable, the amount of sanding necessary is greatly reduced. Furthermore, the strength of the finished string is increased as there is no danger that any one ribbon will project far enough from the other ribbons to have a major portion of its cross section sanded away. The invention, furthermore, produces greater uniformity in the cross section of the finished string since there is no danger of excessive irregularity of contour at some points which will require excessive sanding at those points, while at other points only slight sanding will be necessary. In short, the twisting apparatus and method of this invention produce such a smooth surfaced and round string that only a minimum of abrasion is required throughout the length of the string. It should be observed, furthermore, that even when irregularities appear in the ribbons, the molding plates 44 and 49 will tend to mold out these irregularities.

It is preferred that the molding plates 44 and 49 be provided with a plurality of notches 51, those on the plate 44 opening upwardly and those on the plate 49 opening downwardly. The sides of these notches preferably diverge as shown to facilitate the position of the skeins therein to tend to reduce the skeins to a minimum diameter. Furthermore, the notches 51 may be tapered from end to end, or rather from the left-hand edge of molding plate 44 to the right-hand edge of molding plate 44 with the smaller end at the right so that there will be a tendency to compress the skein more and more tightly as it is twisted. Of course, all of the edges of the various plates 43, 44, 48 and 49 may be rounded off so that no sharp edges will engage the gut. The plates are preferably all made of or plated with a non-rusting metal.

In the use of this invention, the base plates 43 and 44 are first placed in the water-filled tank adjacent to the hooks 13 carried by the rotating spindles 11. Next, the skeins 15 are hooked between the respective portions of hooks 13. Thereafter, the top plates 48 and 49 are set in place, being maintained in position in any suitable manner, as by pins 52. The tension of the respective spacing of the top plates 48 and 49 from the base plates may be preferably adjusted by hand screws 53 threaded on pins 52. These plates may be suitably braced to prevent their

bowing. It may be most convenient to have the pins 52 pivoted to lugs 54 and to have the ends of plates 48 and 49 slotted so that the pins 52 may be swung from a horizontal position to the vertical position shown in Figs. 3 and 4, after which the hand screws 53 may be turned to provide the desired spacing.

The counting switch 34 is set for the desired number of revolutions, and the switch lever 35 is thrown to start the motor 32. This rotates the spindles 11 and the screws 42 so that the skeins are twisted and simultaneously the carriage 41 is moved longitudinally of the tank 10. When the carriage 41 reaches the limit of its movement and the skeins have reached the proper twisted condition simultaneously, the counter switch 34 cooperates to turn off the motor 32. Of course, if desired, the carriage 41 could ride onto the unthreaded portion of the screws 42 at the end of their movement, and the twisting of the skeins could be continued a little longer. After twisting of the skeins is completed, the skeins are removed from the hooks 13 and the carriage is elevated from the screws 42, this being made possible by virtue of the fact that the blocks 47 extend only half way around the screws 42. Thus, it is not necessary to rotate the screws 42 in a reverse direction to return the carriage 41 to the starting position, but, as previously stated, the carriage 41, or rather the base plates 42 and 43, may be set on the screws 42 at the desired position.

Although it is desirable to have the weight of the plates rest at least partially on the screws 42 so as to keep the threads of the screws 42 and the threads of blocks 47 in sufficiently firm engagement, it will be observed that the brackets 46 lie close to the upper edges of the tank 10 so that if the screws 42 would otherwise sag too much under the weight of the plates, part of the weight of the plates will be supported by the tank 10. Of course, if desired, the screws 42 could be supported at a plurality of intermediate points as indicated at 56 so as not to sag appreciably since such supporting is made possible by virtue of the fact that the blocks 47 extend only half way around the screws 42.

In Figs. 6 and 7, a simplified form of the invention has been shown in which the carriage 41 slides along the upper edges or flanges 56 of the tank 10 and is moved manually. In this form, a further simplification has also been shown in that the molding plates 44' and 49' are smooth-surfaced instead of being provided with the notches 51. In short, they may be of the same nature as the clamping plates 43 and 48. The clamping plates 43 and 48 may be provided with screw adjustment, as shown in Fig. 4, or may rely simply on the weight of the upper plate 48. The molding plates have been shown in Fig. 6 as adapted for manual application of pressure to the upper plate 49' when desired. To this end, each bracket 46' associated with the base plates 44' is provided with an extension 57 forming a handle, and the top molding plate 49' is provided with thumb rests 58. Thus, it is possible for an operator to walk along each side of the tank holding the handle 57 to slide the carriage along the tank, and pressing on the thumb rests 58 to provide the desired pressure on the plate 49'.

The operation of this form of the invention is the same as that of Figs. 1-5 except that the plates are moved manually. The operators, however, very quickly acquire the slight skill which

is required for judging the best speed of movement of the carriage by watching the twisting of the skein.

For further simplification, it has been found that the clamps 43 and 48 may be omitted, and in fact, the manual control carriage comprising merely the plates 44' and 49' has been found in actual experience to be very satisfactory.

Figs. 8 to 10 illustrate an additional feature of the invention that may be combined with any of the forms illustrated in the other figures. According to this feature of the invention, a partition plate 61 is positioned during the twisting operation between each pair of adjacent skeins. These partition plates may conveniently all be secured to a hinge plate 62 hinged by a pin 63 to the tank 10. The partition plates 61 may be braced at their outer ends and held at the right depth during the twisting operation by an angle bar 64 which may rest on the sides of the tank 10.

These partition plates are very advantageous in preventing the tied ends of the skein from rubbing against one another as they rotate. Heretofore it has been necessary to space the skeins rather widely apart to prevent them from rubbing against each other. By the use of the partitions it is possible to mount them more closely together. It is believed that they can be spaced with one inch centers. This close spacing of the skeins will make it possible to either provide more skeins in a tank of a given width or use a narrower and hence cheaper and more convenient tank for a given number of skeins.

When the skeins have been completely twisted, the operator grasps the bar 64 and swings the entire partition unit out of the way, as indicated by the dotted lines in Fig. 8. This renders the hooks 13 as easily accessible as if the partitions were not provided. After removing the twisted skeins and attaching fresh skeins, the molding plates 44, etc., may be moved to the starting position and the partition plates swung down onto the molding plate 49, as seen in Fig. 9. A depending portion 65 of each partition plate 61 will in this position extend down between the tied ends of the adjacent skeins so as to separate them at the time that the twisting begins. As the molding plates are moved along the skein, either manually or by screws 42, they will gradually pass out from under the partition plates 61 and let these plates drop to the position shown in Fig. 8, in which they will separate the twisting skeins a little more thoroughly than if they were retained in the position shown in Fig. 10. Of course, if it were desired, the molding plates could be slotted from the right-hand end, so as to let the partition plates fall to their final positions earlier or even initially. Likewise, the molding plates could be corrugated so as to provide deep grooves between the skeins into which the partition plates could fit. In this event the partition plates could extend the full length of the vat so as to avoid any difficulty from a broken strand in a skein.

The knotted end of the twine loop onto which the ends of the ribbons comprising each skein are looped forms a bulky ball, sometimes exceeding a half inch in diameter. Out of this ball extend the tail ends of the ribbons, which, if not cut off very carefully, will fly around during the spinning. These balls and their tails of gut are necessarily side by side, and it is this point where the units contact each other, cause snarling, breakage, and serious tangling. Untangling one of these snarls often takes more time than a total loading, spinning, and unloading operation. The

partitions practically eliminate this trouble, and therefore are really very valuable.

From the foregoing, it is seen that an apparatus and a method have been provided for producing gut strings more efficiently, more economically, and with greater perfection, particularly by molding the string while the skein is being twisted, so that none of the ribbons making up the skein is permitted to extend beyond the circular contour of the string and so that the skein will be shaped to a uniform round contour requiring a minimum of sanding and polishing throughout its length.

It should be recognized that, although the molding features of this invention are preferably used together with the feature of suspending the skeins in water during twisting, they may be used without the water suspension, if desired.

I claim:

1. The process of making gut string which includes twisting a skein of gut ribbons of substantially uniform length in a bath of liquid while applying tension to the skein, and while yieldably applying a molding pressure to a portion of the skein where twisting action is taking place and which has not yet been twisted too tightly to permit readjustment of the ribbons with respect to one another.

2. The process of making gut string which includes stretching a skein of gut ribbons, partially supporting the skein with a bath of liquid to prevent the sagging of some ribbons below others, twisting the skein and while twisting it applying a molding pressure to a side of the portion thereof being twisted, and readjusting the ribbons of the skein with respect to one another to provide an approximately round contour.

3. The process of making gut string which includes stretching a skein of gut ribbons, partially supporting the skein intermediate its ends to prevent the sagging of some ribbons below others, twisting the skein and while twisting it applying a molding pressure to a side of the portion thereof being twisted, and readjusting the ribbons of the skein with respect to one another to provide an approximately round contour.

4. The process of making gut string which includes stretching a skein of gut ribbons, twisting one end of the skein while restraining the other end from twisting, applying a molding pressure first near the twisted end of the skein to mold the portion of the skein being twisted and shifting the point of application of pressure from adjacent the twisted end of the skein to the stationary end of the skein as the twisting action progresses from one end of the skein to the other.

5. In apparatus of the class described, a bath, spaced spindles adapted to hold the skein in the bath, means to tension the skein, means to rotate one of the spindles, and molding means for yieldably applying a molding pressure to a portion of the skein being twisted by the rotation of the spindle.

6. In apparatus of the class described, a bath, spaced spindles adapted to hold the skein in the bath, means to tension the skein, means to rotate one of the spindles, molding means for applying a molding pressure to a portion of the skein being twisted by the rotation of the spindle, and means for moving the molding means longitudinally of the skein.

7. In apparatus of the class described, a bath, spaced spindles adapted to hold the skein in the bath, means to tension the skein, means to rotate one of the spindles, molding means for

applying a molding pressure to a portion of the skein being twisted by the rotation of the spindle, and automatic means operating in timed relation with the rotating spindle for moving the molding means longitudinally of the skein.

8. In apparatus of the class described, a bath, spaced spindles adapted to hold the skein in the bath, means to tension the skein, means to rotate one of the spindles, and molding means for applying a molding pressure to a portion of the skein being twisted by the rotation of the spindle; said molding means including substantially rigid means adapted to yieldingly engage opposite sides of a skein.

9. In apparatus of the class described, a bath, spaced spindles adapted to hold the skein in the bath, means to tension the skein, means to rotate one of the spindles, and molding means for applying a molding pressure to a portion of the skein being twisted by the rotation of the spindle; said molding means including substantially rigid means adapted to engage opposite sides of a skein at points staggered longitudinally of the skein.

10. In apparatus of the class described, a bath, spaced spindles adapted to hold the skein in the bath, means to tension the skein, means to rotate one of the spindles, and molding means for applying a molding pressure to a portion of the skein being twisted by the rotation of the spindle; said molding means including substantially rigid means adapted to engage opposite sides of a skein at points staggered longitudinally of the skein and additional means slidably clamping the skein and positioned beyond the molding means from the rotating spindle.

11. In apparatus of the class described, means for rotating one end of each of a plurality of side-by-side skeins to twist the skeins, molding means for applying a molding pressure simultaneously and jointly to each of the skeins being twisted, and means for moving the molding means lengthwise along the skeins.

12. In apparatus of the class described, means for rotating one end of a skein, and molding means adapted to be moved along the skein from the rotating end and constructed for applying a frictional pressure to the skein effective at one time along a substantial length thereof whereby twisting action takes place within the zone of the pressure as the molding means is moved along the skein.

13. In apparatus of the class described, means to rotate one end of a skein, molding means for applying a frictional pressure to the skein effective at one time along a substantial length of the skein, and means for moving the molding means along the skein away from the rotating end thereof in timed relation to the rotation whereby twisting of the skein will take place in contact with the molding means.

14. In apparatus of the class described, spaced spindles adapted to hold the skein, means to tension the skein, means to rotate one of the spindles, molding means for applying a molding pressure to a portion of the skein being twisted by a rotation of the spindle, and means for moving the molding means longitudinally of the skein.

15. In apparatus of the class described, spaced spindles adapted to hold the skein, means to tension the skein, means to rotate one of the spindles, molding means for applying a molding pressure to a portion of the skein being twisted by the rotation of the spindle, and automatic means

operating in timed relation with the rotating spindle for moving the molding means longitudinally of the skein.

16. In apparatus of the class described, a spindle adapted to hold the skein under tension, means to rotate the spindle, molding means for applying a molding pressure to a portion of the skein being twisted by the rotation of the spindle, and automatic means operating in timed relation with the rotating spindle for moving the molding means longitudinally of the skein.

17. In apparatus of the class described, a plurality of spindles in substantially side-by-side relationship each adapted to hold a skein under tension, means to rotate each spindle, molding means for applying a molding pressure to a portion of each skein being twisted by the rotation of the spindle, automatic means operating in timed relation with the rotating spindle for moving the molding means longitudinally of the skein, and a partition plate resting on the molding means in the starting position thereof and movable, after the molding means has moved, to a position between the ends of the rotating skeins and movable, after the molding means has moved, to a position between additional portions of the skeins and biased toward said position whereby it will automatically move to said position as the molding means moves.

18. In apparatus of the class described, a plurality of spindles in substantially side-by-side relationship each adapted to hold a skein under tension, means to rotate each spindle, molding means for applying a molding pressure to a portion of each skein being twisted by the rotation of the spindle, means for moving the molding means longitudinally of the skein, and a partition plate resting on the molding means in the starting position thereof and extending between the ends of the rotating skeins and movable, after the molding means has moved, to a position between additional portions of the skeins and biased toward said position whereby it will automatically move to said position as the molding means moves.

19. In apparatus for making gut string, a plurality of spindles in substantially side-by-side relationship each adapted to hold a skein under tension with its end loose, means to rotate each spindle, and a partition plate extending between the rotating loose ends of the skeins.

20. In apparatus for making gut string, a plurality of spindles in substantially side-by-side relationship each adapted to hold a skein under tension with its end loose, means to rotate each spindle, and a partition plate extending between the rotating loose ends of the skeins and movably mounted to be readily moved out of the way for attaching the skeins to the spindles.

21. In apparatus of the class described, a plu-

rality of spindles in substantially side-by-side relationship each adapted to hold a skein under tension, means to rotate each spindle, molding means for applying a molding pressure to a portion of each skein being twisted by the rotation of the spindle, means for moving the molding means longitudinally of the skein, and a partition plate resting on the molding means in the starting position thereof and movable, after the molding means has moved, to a position between the skeins and biased toward said position whereby it will automatically move to said position as the molding means moves.

22. In apparatus of the class described, a plurality of spindles in substantially side-by-side relationship each adapted to hold a skein under tension, means to rotate each spindle, molding means for applying a molding pressure to a portion of each skein being twisted by the rotation of the spindle, means for moving the molding means longitudinally of the skein, and a partition plate extending between the ends of the rotating skeins.

23. Apparatus for making gut strings having a plurality of spindles in substantially side-by-side relationship, and means for rotating each spindle, and in which a skein is attached to each spindle by means which leaves the end of the skein loose, characterized by a partition plate extending between the loose ends of the skeins as they are rotated by the spindles.

24. Apparatus for making gut strings having a plurality of spindles in substantially side-by-side relationship, and means for rotating each spindle, and in which a skein is attached to each spindle by means which permits the end portion of the skein to gyrate due to centrifugal force as the spindle is rotated, characterized by a partition plate extending between the ends of the skeins as they are rotated by the spindles.

25. In apparatus of the class described, spaced spindles adapted to hold the skein, means to tension the skein, means to rotate one of the spindles, molding means for applying a molding pressure to a portion of the skein being twisted by the rotation of the spindle, and automatic means operating in timed relation with the rotating spindle for moving the molding means longitudinally of the skein comprising a pair of generally horizontal screws extending generally parallel of the skeins and driven in timed relation to the spindles, a threaded block engaging the upper portion on each screw, moved thereby, and moving the molding means, said block leaving the lower portion of the screw exposed, and support means for the screw at a position intermediate its ends engaging the lower exposed portion of the screw for supporting the same.

CARL G. BJORKMAN.
